US00D769895S

(12) United States Design Patent (10) Patent No.: US D769,895 S
(45) Date of Patent: * Oct. 25, 2016

(54) DISPLAY SCREEN OR PORTION THEREOF WITH GRAPHICAL USER INTERFACE

(71) Applicant: Samsung Electronics Co., Ltd., Suwon-si, Gyeonggi-do (KR)

(72) Inventors: Su-Hyun Na, Seoul (KR); Na-Ri Kim, Seoul (KR); Olivia Lee, Seoul (KR)

(73) Assignee: SAMSUNG ELECTRONICS CO., LTD. (KR)

() Term: 14 Years

(21) Appl. No.: 29/504,551

(22) Filed: Oct. 7, 2014

(30) Foreign Application Priority Data

Apr. 8, 2014 (KR) 30-2014-0017512

(51) LOC (10) Cl. 14-04

(52) U.S. Cl.

USPC D14/485

(58) Field of Classification Search

USPC D14/485-495

CPC H04M 1/2477; G06F 2203/04807;

G10H 1/0008
